UNITED STATES PATENT OFFICE.

MILTON E. OPPENHEIMER, OF NEW YORK, N. Y.

DESIGN FOR A CLUSTER-SETTING FOR GEMS.

SPECIFICATION forming part of Design No. 24,678, dated September 17, 1895.

Application filed June 27, 1895. Serial No. 554,272. Term of patent 14 years.

To all whom it may concern:

Be it known that I, MILTON E. OPPENHEIMER, a citizen of the United States, residing at New York, in the county and State of New York, have invented and produced a new and original Design for Cluster-Settings for Gems, of which the following is a specification, reference being had to the accompanying drawing, in which—

Figure 1 is an inverted plan view, and Fig. 2 a side elevation representing my design.

Open cluster-settings for gems have usually been made with flat or nearly flat back portions and straight sides.

The leading feature of my design for a cluster-setting is the design of the central circular wall with arms extending out radially and having nearly flat front surfaces and back surfaces that are curved from the central wall to the front surfaces of the arms and grooved.

The central ring or wall A is approximately circular and the arms B extend outward and substantially radial therefrom. The front surfaces of the arms are nearly flat and coincide with the front surface of the central ring or wall, and the back edges of the arms are curves extending from the back edge of the central ring to the front surfaces of the arms, as shown, and said back surfaces are grooved, and at the intersections of the back and front surfaces are the claws C.

What I claim is—

The design for a cluster setting for gems, substantially as shown and described.

Signed by me this 21st day of June, A. D. 35 1895.

MILTON E. OPPENHEIMER.
